CLAIM

The ornamental design for a jar for cosmetic products, as shown and described.

DESCRIPTION

FIG. 1 is a top plan view of design for a jar for cosmetic products showing my new design;

FIG. 2 is a right side elevational view thereof, the side opposite being identical except for the appearance of the human figure;

FIG. 3 is a rear elevational view thereof; and,

FIG. 4 is a bottom plan view thereof.
